UNITED STATES PATENT OFFICE.

JOSEPH ARTHUR PAYETTE, OF PROVIDENCE, RHODE ISLAND, ASSIGNOR, BY MESNE ASSIGNMENTS, TO GENERAL CHAIN COMPANY, OF PROVIDENCE, RHODE ISLAND, A CORPORATION OF MASSACHUSETTS.

MACHINE FOR MAKING METAL FABRIC.

1,352,913.

Specification of Letters Patent. Patented Sept. 14, 1920.

Application filed July 23, 1917. Serial No. 182,192.

To all whom it may concern:

Be it known that I, JOSEPH ARTHUR PAYETTE, a citizen of the United States, and resident of the city of Providence, in the county of Providence and State of Rhode Island, have invented certain new and useful Improvements in Machines for Making Metal Fabric, of which the following is a specification.

10 This invention relates to machines for making flexible metal fabric formed of two sets of links, one being interlocked with the other, providing a fabric used largely in the jewelry art.

15 One of the objects of this invention is to provide a horizontal platen over which a continuous loop of fabric is fed and to provide anti-friction fabric supporting rolls on the edges of the platen to insure a more perfect fabric-feeding action.

20 A further object of the invention is to provide a rotatable feeding member which is in constant feeding engagement with the fabric instead of alternately engaging and releasing the same while performing the feeding operation.

25 A further object of the invention is to provide a carrier plate into which the lock link is deposited with means for rotating this carrier and means for positively preventing a retrograde movement of the carrier after each rotating action.

30 A still further object of the invention is to provide means for bending the four prongs of the lock link over to engage the four adjacent ring links and to provide means for slightly separating the prongs to admit of a more effective soldering operation.

35 40 The invention further consists in the provision of means for positioning the last fed ring link by the next succeeding stroke of the ring feeder.

45 With these and other objects in view, the invention consists of certain novel features of construction, as will be more fully described, and particularly pointed out in the appended claims.

50 In the accompanying drawings:

Figure 1 is a plan view of my improved metal fabric making machine.

Fig. 2 is a side elevation partly in section showing the three plungers for operating upon the lock link.

Fig. 3 is a detail showing the general arrangement for rotating and locking the carrier plate. 55

Fig. 4 is an enlarged detail showing the lock link storage hopper, the feed bar and the plunger for bending up the prongs of 60 this link and depositing it in the carrier.

Fig. 5 is a view illustrating the ring link hopper, the ring feed and the plunger which raises the bent lock link from the carrier to position its prongs through the four adjacent ring links to be subsequently clenched thereover. 65

Fig. 6 shows one of these lock links with the prongs upturned.

Fig. 7 shows the link with the prongs 70 partly bent into locked position.

Fig. 8 is a view of the working end of the prong-folding plunger.

Fig. 9 is an enlarged detail in section showing the spur in the center of the prong-folding plunger for slightly separating the ends of the prongs to better permit the depositing of solder therein to facilitate the soldering action. 75

Fig. 10 is a plan view illustrating a portion of the table over which the fabric is fed, and showing the anti-friction rollers on each edge thereof. 80

Fig. 11 is an end view of the table illustrating the general continuous loop arrangement of the fabric in which form the links are applied to the margin thereof without interrupting the continuity of the operation. 85

Fig. 12 is a view showing the end of the 90 fabric table and illustrating the rotatable fabric-advancing mechanism.

Fig. 13 is a plan view of the mechanism illustrated in Fig. 12.

Fig. 14 is a front view of the plunger 95 mechanism which performs the bending of the lock link and the depositing of the same into the carrier.

Fig. 15 shows the bearing of this plunger as mounted in a gate member, which member is shown as being swung back on its hinges to facilitate the clearing of the lock link bending die when clogged. 100

Fig. 16 is a detail showing the side elevation of the prong closing plunger. 105

Fig. 17 is a section on line 17—17 of Fig. 16 showing the circular adjustability of the closing plunger.

Fig. 18 is a view looking at the bottom end of the closing plunger.

Fig. 19 is an enlarged view of the cam which operates the closing plunger showing 5 the extra protuberance on the cam for imparting an extra blow to the plunger for positively bending the prongs of the lock link to a horizontal position.

Fig. 20 is a top view illustrating the lock 10 link feeding member and the die opening in the table through which the bending plunger forces the link to turn its prongs upward and to deposit it into the carrier below.

Fig. 21 is a plan view showing a section 15 of the fabric supporting table, a section of fabric on the table and the combined ring-link feeding and positioning tool.

Fig. 22 is a view showing the back side 20 of a section of fabric.

Fig. 23 is an edge view of the fabric showing the prongs of the lock link before they have been finally rolled down into position.

Referring to the drawings, 25 designates 25 the bed of the machine upon which the cam shaft 26 is mounted in bearings 27, which shaft is driven through the pulleys 28, and on this shaft is mounted the various cams 30 necessary for operating the mechanism hereinafter described.

In the operation of my improved fabric forming machine I employ two styles of 35 links, one in ring form illustrated at 29, see Figs. 21 and 22, cut out from flat stock, while the other is in substantially the form of a cross illustrated at 30 in Fig. 20, also cut from flat stock having four fingers adapted to be bent up, passed through the 40 ring-links and turned over to loosely lock the links together. This cross form of link will be hereinafter called the "lock link".

In handling this lock link I provide a 45 long tube 31 square in cross section in which these links in flat form are stored, the lowermost link resting upon the feeder bar 32, which bar is of substantially the same thickness as the link. The ring links 29 are stored in a circular tube 33, the lower link 50 resting upon the feeder plate 34. A carrier disk plate 35 is mounted beneath the bed 25 and is provided with a series of holes 36 about its outer edge, which holes are adapted to register both with a die hole 37 55 and a return hole 53 through the bed. This plate is provided with a step by step rotation by the cam 38 acting through the bar 39 upon the spring-pressed pawl 40, which pawl engages the ratchet teeth 41 in the 60 edge of the plate.

It is found in practice that when this pawl is being advanced for another tooth, by means of a spring (not shown), the friction of this pawl in running back over the 65 teeth of the plate has a tendency to move

the plate back out of adjusted position and sometimes a quick feeding movement carries the plate ahead beyond its registering position, either of which actions interferes with the proper operation of the machine. 70 Therefore to obviate this serious difficulty I have provided a series of separate and independent V-shaped peripheral teeth 42 which are engaged by a correspondingly shaped pawl 43, withdrawn by cam 44 75 through the cam bar 45 and advanced to engaging position by spring 45^a, which pawl positively positions the plate to cause its link receiving holes to accurately register with the die holes in the bed. In order to 80 feed the lock links, the feeder bar 32 is withdrawn by means of the cam 46 through the action of roll 47 and slide bar 48, from beneath the pile of lock links permitting the action of gravity on the pile of links to 85 force the lower link down into the path of the feeder bar so that when the bar is released by the cam 46 it is moved forward through the action of spring 49 to move this link over the die opening 37. Here this 90 link is engaged by the plunger 50 which is actuated through cam 51 and lever arm 52, pivoted at 52^a, to force the link down through the die opening 37 into the opening 36 of the carrier 35, causing the link 95 fingers to be bent upward into the position best illustrated in Fig. 6. This carrier is now advanced through its pawl and ratchet mechanism step by step and when the link so bent, arrives at the second opening 53 100 in the bed, a second plunger 54 beneath the bed, which is operated from the cam 55 through the lever arm 56, pivoted at 56^a, see Figs. 1 and 2, engages the under side of this link and forces the same upward so that 105 each of its four prongs will pass up through each of the adjacent four ring links, see Fig. 21, which have been previously positioned to receive these prongs. The plunger 57 having a cup-shaped lower end 58, is 110 now forced downward by means of the cam 59, through the lever 60, pivoted at 60^a, to fold these fingers inwardly and close them over the ring links.

The ring links are first moved similar to 115 the lock links above described, in that the ring-link feed bar 34 is withdrawn at the proper time by means of cam 61, cam roll 62 and long bar 63, permitting the pile of links under gravity action, to force the 120 lower link *c* down into the path of movement of the ring feeder, so that when released by this cam, the spring 64 causes the feeder to advance this ring *c* in its path, into the dotted position illustrated in Fig. 125 21.

It is found in practice that while advancing the fabric into position to receive the next two links, that is one ring link and one lock link, the marginal link *a* has a 130

tendency to move out of its proper relative position, that is, from the dotted to the full line position, in which latter position the prongs of the lock link cannot well pass through it. Therefore to obviate this difficulty I have provided the feeder member 34 with a second recessed opening 65, and an extending finger 66 adapted to engage this displaced ring α and move it down into proper position, at the same time it is positioning the fresh link c .

By means of these two link-feeding mechanisms, it will be seen that immediately after the fresh ring link is positioned at the margin of the fabric, that the lock link is forced upward by the plunger 54, its prongs passing through this fresh link and also through three of the links previously attached to the fabric, the prongs of this lock link are then engaged by the plunger 57, bending them inwardly and loosely connecting the said four rings together. The fabric is then advanced, and another ring link is positioned and another lock link is caused to engage the next four ring links, as above described, after each feeding operation of the fabric.

A narrow table 67 extends outward from the bed of the machine to serve as a support over which the fabric is fed while the links are being attached to its margin. It is found in practice to be of great advantage to form this fabric in a continuous band, as illustrated at b in Fig. 11 so that the continuity of the operation of the machine may be uninterrupted; that is if the fabric were not in band form the operator would have to start the machine over again each time it reached the end of the fabric, but by forming the fabric in a band the operation is continuous. By providing a narrow table or support for the fabric and allowing the loop to hang thereover the length of this band is entirely unrestricted and the width only limited by that of the table.

It is found in practice that where a long band is hanging from the edges of the table that its weight creates considerable friction and in some cases prevents the proper operation of the mechanism, therefore, to overcome this objection I have provided anti-friction rolls 68 which support the weight of the fabric and over which the fabric may be readily drawn. Then again to further reduce the friction of this fabric I have cut away the opposite edge surfaces of the table at 69, so as to permit the rolls to carry the greater portion of the weight and permit only that portion of the fabric which is being operated upon, to rest upon the table.

One of the features of this invention is the mechanism by which the fabric is advanced step by step, and that without releasing it during the feeding action. To

accomplish this I have provided a corrugated roll 70 the surface of which is provided with longitudinally disposed teeth adapted to enter the spaces between the rows of links. This roll is provided with trunnions 71 mounted in elongated openings 72 in the bearing arms 73, which trunnions are under tension of the flat springs 74 to yieldingly press the feed roll onto the fabric.

In order to rotate this feed roll intermittently, I have provided a rack-arm 75 which is connected by the pin 76 to the sliding block 77, and this block is given an intermittent reciprocating motion from the cam 78 through the arm 79, pivoted at 79^a, whereby as the cam rotates it forces the arm 75 to the right, and when this arm is released by the cam, it is withdrawn by means of the spring 80.

I have arranged that this rack-arm shall engage and release the teeth of this roll at the proper time, which is accomplished by means of the cam 81 acting through roll 82 upon the bar 83, pivoted at 83^a, the free end of which bar is connected to the pin 84 on this arm 75 so that just before the rock arm is moved to the right, it is dropped into contact with the teeth of the roll and just before it is moved back to the left it is raised from contact with the roll, therefore, the roll receives an intermittent rotation for imparting a step by step longitudinal feeding movement to the fabric without releasing the fabric.

When it is desired to raise the roll and release the fabric in order to re-set, adjust or otherwise manipulate the same by hand, it is only necessary to withdraw the pawl 91 by the handle 96 against the tension spring 92, from the opening 93 in the arm 73, whereby both of the supporting arms may be swung on their pivot screws 94 to raise the roll from the fabric.

It is found in practice in the continued bending up of the prongs of the different lock links that some become displaced and the die opening becomes clogged, and in order that the clogging members may be readily removed and cleared from the die, I have mounted the plunger 50 in a block 85 and hinged this block at 86 to its post 87, whereby it is only necessary to withdraw the lock pin 88, see Fig. 14, from one side of the block, to swing its plunger quite clear and out of the way of the die opening 37, thereby rendering the clogged opening quite accessible.

In some instances it is found necessary to bend down the prongs of the lock link to further close the same and, therefore, I have provided a protuberance 89 on the cam 59, which causes the die to strike a second blow and so more perfectly close the fingers flatly over the rings.

In some instances where very fine mesh is made it is found desirable owing to the delicacy of the stock, necessary to solder the ends of the fingers together, and in such cases it is found desirable to slightly separate the extremities or abutting ends of the fingers so that a small portion of the solder may work its way down between these fingers to render the soldering action more effective. Therefore to accomplish this I have formed a spur 90, see Figs. 8 and 9, on the inner surface of the bending plunger, whereby the finishing downward stroke of the plunger will slightly separate the ends of the fingers.

The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. In a machine for making link-mesh fabric, a plunger for folding the arms of the lock-link when in engagement with the ring-links, and a spur in said plunger for maintaining a slight separation at the ends of the arms when folded to facilitate soldering.
2. In a machine for making link mesh fabric, means for supporting a set of ring links, means for supporting a set of pronged links, means for successively positioning the ring links to the margin of the fabric being formed and simultaneously repositioning the ring next previously fed, and means for subsequently passing the fingers of the pronged link through three rings in the fabric and also the last ring fed.
3. In a machine for making link-mesh fabric, means for supporting a set of ring-links, means for supporting a set of pronged links, a double grooved feed plate for successively positioning the ring-links to the margin of the fabric being formed and

simultaneously repositioning the ring next previously fed, and means for subsequently passing the fingers of the pronged link through three rings in the fabric and also the last ring fed.

4. In a machine for making link mesh fabric, a table for supporting a piece of the fabric, means for feeding the links to the fabric, clenching tools for attaching the links to the margin of the fabric, a rotatable feeder member in constant feeding engagement with the fabric for sliding it intermittently over the table and into position to be operated upon by said tools and a spring for maintaining the feeder in yielding engagement with the fabric.

5. A machine for making link mesh fabric comprising a horizontal platen over which a continuous loop of fabric is fed, means for attaching links to the margin of the fabric as advanced over said platen, a corrugated roll in constant feeding engagement with the links of the fabric, a reciprocating member for rotating said roll intermittently to advance the fabric step by step over said platen relative to said link-attaching means and means for maintaining said roll in yielding engagement with the fabric.

6. A machine for making link mesh fabric comprising a horizontal platen over which a continuous loop of fabric is fed, means for attaching links to the margin of the fabric as advanced over said platen, a corrugated roll having teeth in constant feeding engagement with the fabric links, a reciprocating member engaging said roll intermittently to rotate it and so advance the fabric step by step relative to said link attaching means, and means whereby said roll may be raised to release the fabric when desired.

In testimony whereof I affix my signature in presence of a witness.

JOSEPH ARTHUR PAYETTE

Witness:

HOWARD E. BARLOW.
